United States Patent

Des. 241,443
Patented Sept. 14, 1976

241,443

DENTAL FLOSS APPLICATOR

Charles R. Russell, 3071 Marilyn Way,
Santa Barbara, Calif. 93105

Filed Sept. 24, 1974, Ser. No. 508,745

Term of patent 14 years

Int. Cl. D24—99

U.S. Cl. D24—1 D

FIG. 1

FIG. 2

FIG. 3

FIG. 4

FIG. 1 is a top plan view of a dental floss applicator, showing my new design;

FIG. 2 is a side elevational view thereof;

FIG. 3 is a right end elevational view thereof on an enlarged scale; and

FIG. 4 is a bottom plan view thereof with the dental floss in place, and set forth in broken lines for illustrative purposes only.

The left end of the applicator is substantially flat and unornamented.

I claim:

The ornamental design for a dental floss applicator, as shown and described.
